UNITED STATES PATENT OFFICE.

EDWARD N. LICHTENSTEIN, OF BALTIMORE, MARYLAND.

FOUNTAIN BATH BRUSH.

Application filed October 27, 1921. Serial No. 510,736.

To all whom it may concern:

Be it known that I, EDWARD N. LICHTENSTEIN, a citizen of the United States, residing at Baltimore, in the county of Baltimore 5 City and State of Maryland, have invented certain new and useful Improvements in Fountain Bath Brushes, of which the following is a specification.

My invention relates to an improved construction in fountain bath brushes.

An object of the present invention is to provide a fountain bath brush to which a water supply tube of the ordinary type may be easily and readily attached to a spigot 15 or other means for the supply of a liquid to the brush bristles.

A further object of the present invention is to provide a fountain bath brush which may be used with a portable bath apparatus 20 for use in rural communities where the usual facilities for bathing, including running water, bath tub and other modern conveniences may be found, and one which is simple in design, cheap to manufacture, and the 25 simplicity of design and rigidity and strength of the structure rendering the fountain bath brush a desirable and useful article.

A still further object of this invention is 30 to provide an improved fountain bath brush with a detachable handle which readily facilitates thorough cleaning of the same.

With the foregoing and other objects in view, which will appear as the description 35 proceeds, the invention resides in the combination and arrangement of parts and the details of construction hereinafter described and claimed.

In the drawings, wherein like reference 40 characters indicate like or corresponding parts,

Figure 1 is a side elevation of the improved construction of my fountain bath brush.

Fig. 2 is a longitudinal sectional view of the same,

Fig. 3 is a transverse sectional view of the brush,

Fig. 4 is a top plan view of a modified 50 form of construction,

Fig. 5 is a detail perspective view of the brush handle showing the longitudinal groove,

Fig. 6 is a detail perspective view of the 55 brush showing the wedge shaped channel and longitudinal groove, and

Fig. 7 is a modified form of constructing the handle.

Referring to the drawings, my improved fountain bath brush construction consists of a brush 1, having the usual bristles 2, said bristles being provided with a central orifice 3 adapted to receive the nozzle 4 of a liquid supply pipe 7, said supply pipe being bent downward as at 9 in order to allow the nozzle 4 which is of a diameter small enough to pass freely through the orifice 3, and is provided at one end with a flanged nozzle cap 5, having the usual perforations therein, and at the opposite end with an internally threaded 70 hose nipple which is connected with the rubber supply hose 12 which in turn is adapted to be connected to any source of water supply.

The brush 1 is provided with a detachable handle 15 having a longitudinal groove 16 to rest over the supply pipe 7 and retain the same rigidly in place. The back of the brush 1 is provided with a converging channel 17 and a longitudinal groove 18 extending to the orifice 3 for the reception of the supply pipe 7. The handle 15 is shaped to conform with the converging channel 17 whereby a wedging effect is accomplished, and which, when in place, holds the brush and parts in assembled relation and ready for use.

In the modified form disclosed in Figure 4, the brush 1 is provided with the rubber supply hose 12, the supply pipe 7, the orifice 3 and the other detailed construction disclosed in Figure 3. In this modified form I propose to provide the brush 1 with a series of apertures 20 extending through the brush to allow water to seep therethrough which will assist in preserving the brush proper. I also use in this modified form a wedge 22, doing away with the handle 15 and using in place thereof a hand strap 23. This wedge 22 is also provided with a longitudinal groove 16 as disclosed in Figure 3 and the converging channel 17.

Referring to the modified form of handle disclosed in Figure 7, the handle 15 is provided with the longitudinal groove 16 and its outer end is extended at right angles as at 21 which will allow ready access and manipulation of the brush to one's back.

When it is desired to use this improved fountain bath brush, remove the handle 15 from the channel 17, insert the supply pipe 7 with its nozzle 4 extending through the orifice 3, and the pipe 7 resting in the longi-

2
tudinal groove 16. When this has been done, take the handle 15 and place the longitudinal groove 16 over the supply pipe 7 and proceed to wedge the same in the converging channel 5 17 of the brush 1. When this has been accomplished you now have the fountain bath brush in assembled relation and ready for use.

Having thus described my invention, it is 10 obvious that various immaterial modifications may be made in the same without departing from the spirit of my invention, hence I do not wish to be understood as limiting myself to the exact form, construction, 15 arrangement and combination of parts herein shown and described.

What I claim as new and desire to secure by Letters Patent is:

1. In a device of the kind described comprising in combination, a brush back 20 provided on its upper side with a converging wedge-shape channel extending longitudinally from one edge thereof, the side walls of said channel being undercut, said brush back being further provided with an orifice 25 opening from the lower face of said back into said channel, and a groove formed in the bottom wall of said channel and extending from one edge of the brush back and 30 communicating with the orifice, a supply tube adapted to rest in said longitudinal groove, a rubber tube connected to said supply tube, a handle provided with a longi-

tudinal groove, said handle being so constructed as to slide longitudinally within 35 said converging wedge-shaped channel member to hold the brush and parts rigidly in position.

2. A bath brush including a back having a converging channel, a longitudinal groove in said channel and extending to an orifice 40 centrally located in the back of said brush, a supply tube resting in said longitudinal groove and bent downwardly through said orifice, a handle adapted to slide longitudinally within said converging channel provided with a longitudinal groove to receive 45 said pipe for holding said parts in assembled relation.

3. In a device of the kind described, comprising in combination a brush back having a central orifice, an elongated converging channel communicating with said orifice and extending from an edge of the brush back, 50 an elongated groove in said channel and also communicating with said orifice, a supply pipe adapted to rest in said groove and having a portion adapted to pass through said orifice, a wedge-shaped member adapted to slide longitudinally within said channel and 55 provided with a groove adapted to receive the said pipe for holding it in assembled position.

In testimony whereof I hereunto affix my signature.

EDWARD N. LICHTENSTEIN.
